(57) **CLAIM**

We claim the ornamental design for a receptacle, as shown and described.

DESCRIPTION

FIG. 1 is a front perspective view of a receptacle, with an exemplary lid, showing the new design;
FIG. 2 is a front perspective view of the receptacle of FIG. 1,

FIG. 3 is a top perspective view of the receptacle of FIG. 2,
FIG. 4 is a bottom perspective of the receptacle of FIG. 2,
FIG. 5 is an enlarged view of the designated circular area of FIG. 4;

FIG. 6 is a left side view of the receptacle of FIG. 2, the right side view being essentially a mirror image thereof;

FIG. 7 is a front view of the receptacle of FIG. 2, the rear view being essentially a mirror image thereof;

FIG. 8 is an enlarged view of the designated circular area of FIG. 7;

FIG. 9 is a top view of the receptacle of FIG. 2; and,

FIG. 10 is a bottom view of the receptacle of FIG. 2.

The broken lines in the drawings depict environmental features of the receptacle that form no part of the claimed design.
